CLAIM

The ornamental design for scissors, as shown and described.

DESCRIPTION

FIG. 1 is a perspective view of scissors, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings depict portions of the article that form no part of the claimed design.

The dash-dot broken lines shown in the drawing depict the boundary of the claimed design and form no part of the claimed design.
